Albert Harold Gilliam, Alameda, Calif.

Application October 9, 1944, Serial No. 115,692

Term of patent 3½ years

(Cl. D34—2)

To all whom it may concern:

Be it known that I, Albert Harold Gilliam, a citizen of United States of America, residing at 364A Singleton Avenue, Alameda, in the county of Alameda and State of California, have invented a new, original, and ornamental Design for Toy Horse, of which the following is a specification, reference being had to the accompanying drawing, forming part thereof.

In the drawing

Fig. 1 is a front elevational view of a toy horse, showing my new design.

Fig. 2 is a side elevational view thereof.

I claim:

The ornamental design for a toy horse, substantially as shown.

ALBERT HAROLD GILLIAM.
